STORAGE TUBE CONSTRUCTION**Dean W. Davis, Fort Wayne, Ind., assignor to International Telephone and Telegraph Corporation**

Application January 3, 1955, Serial No. 479,329

6 Claims. (Cl. 315—12)

The present invention relates to storage tubes, and more particularly to a construction wherein improved image reproduction is achieved.

A storage tube of the type contemplated by this invention is disclosed and claimed in Farnsworth Patent No. 2,228,388, granted January 1, 1941. The tube of this invention may take one of two forms, viz., a "signal-to-image" tube or a "signal-to-signal" tube. By "signal-to-image" is meant that the tube will reproduce an electrical signal in the form of a visible image, whereas a "signal-to-signal" tube is one wherein an electrical image signal is reproduced in the form of an electrical signal. From the following explanation of this invention, it will be evident that the principles may be adapted to either type of tube for achieving improved performance.

It is an object of this invention to provide an image-amplifying tube wherein a material improvement in uniformity of the reproduced image or signal is achieved.

It is another object of this invention to provide an image-amplifying tube wherein a material improvement is achieved in the distribution of brightness over the area of the signal electrode, this signal electrode being either a phosphor screen or a metallic plate.

In accordance with the present invention, there is provided for use in an electron discharge device a perforate storage element having a surface area for providing an electrostatic charge image, a utilization electrode disposed adjacent to said storage element and having an electron-receiving surface which is juxtaposed with respect to said storage element surface area, and means included with said element and said electrode for equalizing electron current flow therebetween for achieving cross-sectional uniformity in the beam received by the utilization electrode.

To the accomplishment of the above and related objects, my invention may be embodied in the forms illustrated in the accompanying drawings, attention being called to the fact, however, that the drawings are illustrative only, and that specific change may be made in the specific constructions illustrated and described, so long as the scope of the appended claims is not violated.

In the drawings:

Fig. 1 is a sectional illustration of one embodiment of this invention; and

Fig. 2 is a fragmental sectional view of the storage screen thereof.

Referring to Fig. 1, the cathode ray storage tube comprises an envelope 1 having an enlarged cylindrical body portion 2 and a smaller diameter angularly extending neck portion 3. Mounted in the end of the neck 3 is a beam-forming electron gun assembly 4 which generates a beam of electrons for covering an elemental area only of an image storage screen generally indicated by the reference numeral 5. A flood electron gun is mounted at the rear end of the envelope portion 2 and is so arranged as to emit a flood of electrons which will cover either a substantial portion or the entire area of the screen 5. A luminescent screen 7 of conventional design and

2

which fluoresces under the impact of electrons is provided in the envelope portion 2 at the end opposite the flood gun 6. In tubes adapted to provide an electrical signal output rather than an optical display, an ordinary conductive plate may be substituted for screen 7. The term "utilization electrode" as used in the claims is intended to include both the screen 7 and such conductive plate. A conductive coating or anode 8 is provided internally of the envelope portions 2 and 3 for the purpose of controlling the beams from both guns as is generally accomplished in conventional cathode ray tubes.

A perforate collector electrode 9 of relatively large mesh size and transmissivity is mounted adjacent the storage screen 5 on the electron gun side.

With suitable potentials applied to the electrodes thus far described, a positive charge image may be impressed on the storage screen 5, by impacting writing beam electrons, it is simultaneously being flooded by electrons from the gun 6, the flood gun being maintained at a potential slightly positive with respect to left-hand side of the screen 5. The electrons flowing therefrom will not be attracted to the screen itself but instead will pass through the screen openings, to impinge the luminescent anode 7. As the flood electrons pass through the respective screen perforations, they are modulated in number in accordance with the elemental charges surrounding the corresponding perforations and will, therefore, impinge against the luminescent anode 7 with a density dependent upon such modulation. By this means, the charge image on the screen is optically reproduced on the anode 7.

Continuing with the detailed description, the screen 5, as seen in Fig. 2, is comprised of a metallic screen 10 of, for example, 500 mesh size, one side of this screen being covered by a dielectric material 11, such as quartz. For exact details of construction of this screen and of the other tube structure, reference may be made to Farnsworth application Serial No. 197,612, filed November 25, 1950, now Patent No. 2,754,449.

40 A magnetic focusing coil 12 of conventional design surrounds the neck 3 for focusing the beam from the gun 4 onto the screen 5, and a suitable pair of deflection coils (only one coil 13 is shown) also surrounding the neck 3 are mounted adjacent the focusing coil 12 for controlling beam scansion of the screen 5. In this connection, any well-known raster-forming scanning techniques may be utilized.

The gun assembly 4 is comprised of a cathode element 14, a control element 15, and an accelerating anode 16. 50 The flood gun assembly 6 is comprised of a cathode 17 and an accelerating anode 18, these parts being so arranged as to direct the electron flow from the cathode 17 over the entire front face of the screen 5.

55 Input video frequency signals derived from a suitable video circuit represented by the block 19 may be applied through a condenser 20 to the control grid 15. A negative biasing battery 21 is connected through a resistor 22 to the control grid 15, and a cathode biasing battery 23 is connected between ground and the cathode 14 with the minus terminal of the battery 23 being connected to the positive terminal of the battery 21. Anode 16 voltage is supplied by battery 37 having a negative terminal which is connected to the negative terminal of battery 23. A conventional scanning wave generator capable of generating a current of sawtooth wave form is conductively connected to the deflection coil 13 for controlling the scanning movement of the electron beam.

The luminescent anode 7 is supplied with a relatively high potential from a battery 26. Another battery 27 has its positive terminal connected to the metal backing 10 of the storage screen 5 (Fig. 2). However, the potential of the front (insulating) side of the storage screen is

the more important factor in the operation of the tube than is that of the metal backing, and it has been found that, under some conditions, the polarity of battery 27 may be reversed. The collector electrode 9 has a positive potential applied from the battery 28. The conductive coating 8 inside the tube is provided with a positive potential from battery 29. The anode 18 is positive by connection to battery 36. The cathode 17 is connected through a resistor 31 to ground which is common to all of the negative terminals of the last-mentioned batteries. Cathode 17 is further coupled through a capacitor 32 to an "erase pulse" generator 33, which is of conventional design, for supplying a square wave pulse. This "erase pulse" generator 33 may be a one-shot multivibrator which is triggered into single cycle operation by a wave derived from the aforementioned scanning wave generator.

In operation, the beam of electrons emitted by the electron gun 4 is scanned over the screen 5 in the usual raster forming manner by means of the deflection coils. The electrons in this beam are caused to travel at such velocity as to produce greater than unity secondary emission on the impinged elemental areas of the screen insulator 11, so that as the beam is scanned over the area of the screen, a charge pattern of positive potential is formed. The low velocity electrons from the flood gun 6 are attracted toward the luminescent anode 7 by reason of the relatively high potential applied thereto, these flood electrons passing through the mesh openings of the screen 5 before striking the screen 7. The number of flood electrons passing through the individual mesh openings are modulated in accordance with the charge pattern on the screen, the modulated electron flow thereby representing the charge pattern on the screen 5 and serving to excite the display of an equivalent image by the screen 7.

During reproduction of the image on screen 7, the potential relationship between the cathode 17 and storage element 5 is such that the electrons reach element 5 with a low velocity. This velocity is adjusted to be such as will not cause impingement of the flood electrons on the charged screen 5 but instead will merely form a cloud of electrons (or virtual cathode) adjacent the charged face of the screen 5. The electrostatic field produced by the anode 7 may be considered to "reach" through the apertures of the screen 5 and draw the flood electrons therethrough. It has been found that in order to achieve suitable flood electron velocity, the cathode should be preponderantly positive; meaning that for the most part the elemental image charges on the screen 5 are at a negative potential with respect to the cathode 17. Further, the metallic backing 10 of screen 5 may be operated slightly positive with respect to cathode 17 at a value which has been found should not exceed a few volts. However, the exact potential relationship between cathode 17 and screen 5 will depend upon tube operating requirements.

An image pattern is formed on the screen 5 at the completion of the effective vertical scanning cycle applied to the deflection coil 13. Since it is desired to erase this charge image prior to the next picture-forming scanning, the retrace portion of the scanning wave is utilized to initiate the erasing pulses 34 in synchronism therewith. These erasure pulses 34 are made sufficiently negative so that a difference of potential between the cathode 17 and the charge pattern on the storage screen 5 will be set up which substantially increases the velocity of the electrons emitted from the cathode 17 and causes them to impinge upon the charged areas of the screen. These electrons supply the deficiency of electrons as represented by the positive charge pattern and thereby establish the potential of the screen at a uniform negative value corresponding to the potential of the pulse 34.

This method of pulsing the flood gun for alternately providing "erasing" and "reading" electrons is disclosed and claimed in Farnsworth et al. application

Ser. No. 362,473, filed June 18, 1953. Insofar as is necessary for a complete understanding of this invention, this Farnsworth et al. application is made a part hereof.

Considering for the moment that the anode 7 is a phosphor screen, it has been noted in prior art devices that objectionable shading over the areas thereof appeared. For example, in certain instances the central portion of the screen 7 would be unnaturally brighter than the outer regions. In overcoming this objectionable operation, the spacing between the storage screen 5 and the phosphor anode 7 is varied over the lateral extent thereof as is clearly illustrated in Fig. 1. Having a flat screen 5, it has been found that the phosphor screen 7 should be convexly curved outwardly to vary the aforementioned spacing. The exact degree of variation in this spacing, or stated in other words, the exact degree of curvature of the phosphor anode 7 will vary according to the different sizes and characteristics of the finished tube. However, this curvature may be determined in accordance with the following teachings.

By curving the phosphor anode 7 into the proper shape, the objectionable shading mentioned hereinabove is eliminated, with the consequence that the brightness characteristic over the entire lateral extent of the anode 7 is made uniform.

This elimination of shading is believed to occur for the following stated theoretical reasons. An electrical field exists between the screen 5 and anode 7 which tends to penetrate the openings in the screen 5. These penetrating fields (see the equi-potential lines 35 of Fig. 2) accelerate flood electrons through the respective screen openings toward the anode 7. However, difficulty arises due to the fact that although the velocity of flood electrons in the axial region of the tube may be the same as the velocity for the outer or peripheral regions, the angle which the velocity vector makes with the normal to the plane of the insulator is greater in the outer regions. It is the normally-directed velocity component which determines whether a flood electron will be able to pass through the minimum potential existing in the insulator mesh holes or whether it will be deflected away from the insulator toward collector electrode 9. Therefore, for the same minimum potential in the mesh holes of the two regions, more low velocity electrons normally are attracted to the central region of the anode 7 than for the outer regions, whereupon the central region is unnaturally brighter.

The effects of this differential in electron normal velocity are overcome by increasing field penetration from the anode 7 through the openings of the screen 5 for the outer portions only of the latter. Stated conversely, the accelerating electrical field produced by the anode 7, which reaches through the openings of the screen 5, is made relatively less in the axial region of the screen 5 than for the outer regions. This is achieved by spacing the central portion of the anode 7 farther away from the central portion of the screen 5 than the outer portions, such that a more positive minimum potential is produced in the outer regions between the two elements 5 and 7 than for the central region. The obliquely-directed low velocity flood electrons existing in the outer regions thereby penetrate electrode 5 to the same degree as the normally-directed electrons in the axial region, and by spacing the screen 5 and anode 7 the proper distances apart, an equal number of electrons will reach the anode 7 in all regions. Thus, electron current flow over the lateral extent of the anode 7 is equalized or made uniform, thereby eliminating the objectionable condition of shading.

In some instances, where the flood gun is eccentrically positioned with respect to the storage screen 5, it will be necessary to shape the anode 7 such as to counteract the shading effect produced by the unequal normal electron velocities. It will now be apparent that the particular shape of the anode 7 will vary depending upon the posi-

tion of the flood gun 6 or any other low velocity electron gun used to scan the storage screen 5. This shape is always made such as will produce equal electron densities over the lateral extent of the anode 7 as evidenced by uniform, natural distribution of luminescence or brightness.

The basic concept of this invention, as will now be apparent, resides in correcting for the shading characteristics of the tube, and while one method of achieving this correction is specifically described, other methods will appear as obvious to a person skilled in the art. For example, this correction is achieved by varying the sizes of the openings of the screen 5 over the lateral extent thereof such that for the areas thereof coinciding with low density electron flow, electron transmission through the screen will be increased. This greater transmission also allows greater field penetration from the anode 7, the net result of the increased transmission and penetration being the equalization of electron currents arriving at the anode 7.

What is claimed is:

1. For use in an electron discharge device, a perforate storage element having an extended bi-dimensional surface area treated for providing an electrostatic charge image responsive to bombardment with high velocity electrons, a source of low velocity electrons on one side of said element arranged to flood said surface area thereof, a utilization element disposed adjacent the other side of said storage element and having an electron-receiving surface which is coextensive with said other side of said storage element for receiving said low velocity electrons which pass through said storage element, said electron source having an area which is small with respect to the area of said storage element so that said storage element normally tends to pass a disproportionate electron current in one regional area, one of said elements having its surface curved with respect to the surface of the other element with the distance defined therebetween varying over the surfaces thereof in accordance with the aforesaid disproportionate electron current whereby the electron current passed through said storage element is substantially uniform over the entire surface area thereof.

2. For use in an electron discharge device, two bi-dimensional extended side-by-side electrodes spaced apart and having juxtaposed surface areas, means for applying a control potential between said electrodes which potential produces an electrical field extending from one electrode to the other, a cathode arranged to flood one of said electrodes with low velocity electrons, said one electrode being perforate to pass said electrons received from said cathode, said one electrode having means for providing and storing an electrostatic charge image on one surface area thereof responsive to bombardment of said surface area with high velocity electrons, said cathode having a small area with respect to the area of said electrodes so that said one electrode normally tends to provide a disproportionately greater electron current in one elemental area, one of said electrodes having its surface area curved with respect to the surface area of the other electrode with the distance defined therebetween being greater adjacent said elemental area than for the remaining portions of said surface areas whereby said electrical field provides a uniform cross-sectional flow of electron current between said electrodes over said surface areas.

3. For use in an electron discharge device, two elements spaced apart and having juxtaposed surface areas, means for applying a control potential between said elements which potential produces an electrical field extending from one element to the other, said one element being flat and perforate and including a surface layer

for receiving and storing an electrostatic charge image, a first cathode for bombarding said surface area of said one element with high velocity electrons to impress said electrostatic charge image thereon, a second cathode for covering the charged area of said one element with low velocity electrons which pass therethrough to be received by the other element, said second cathode having a small area with respect to the area of said elements whereby an unequal electron current flow normally tends to pass through said one element over the lateral extent thereof, said other element having its surface curved outwardly with respect to the surface of said one element with the distance defined therebetween varying over the surface thereof in accordance with said unequal current flow thereby to equalize the current flow through said one element over the lateral extent thereof.

4. An electron discharge device comprising a bi-dimensional foraminous grid of substantial area having a secondary-electron emissive charge-storage surface on one side thereof, a point-source of low velocity electrons spaced from and adapted to bombard the entire area of said one side, a phosphor plate spaced from and coextensive with the other side of said grid and adapted to receive electrons moving axially through the perforations of said grid, said plate being concaved with respect to said grid so that the spacing between said grid and plate is progressively less at points removed from the shortest electron-source to grid line.

5. An electron discharge device comprising a point-source of low velocity electrons, a planar-type foraminous grid disposed to be bombarded throughout one side by said source, a planar-type anode electrode coextensive with and spaced from the other side of said grid and adapted to receive electrons through the perforations of the grid, said grid and anode electrode being relatively concaved to produce grid-to-anode spacing and voltage gradients at any point on the grid proportional to the obliqueness of the line from said point to said electron source.

6. In a storage tube: a planar storage screen having a conductive surface and a dielectric surface; an electron gun spaced from said dielectric surface for directing a high velocity electron beam toward said dielectric surface; means for scanning said dielectric surface with said high velocity electron beam thereby impressing a positive charge pattern on said storage screen; a secondary electron emission collector screen positioned between said dielectric surface and said electron gun; an anode spaced from said conductive surface; means for establishing an electrical field between said anode and said conductive surface; another electron gun spaced from said dielectric surface for directing low velocity flood electrons toward said dielectric surface and through the openings in said storage screen onto said anode under the influence of said electrical field whereby said electrons are modulated in accordance with the charge pattern on said storage screen; said anode being concave with respect to said storage screen to provide field strengths increasingly greater toward the outer edge of said anode thereby providing uniform electron flow from said conductive surface to said anode throughout the lateral extent thereof.
